WINDOW CONSTRUCTION

Salvatore Terrasi, Brooklyn, N. Y.

Application March 29, 1933, Serial No. 663,305

2 Claims. (Cl. 20—46)

The invention relates to devices for enabling standard sliding window sashes to be pivotally swung from the window frame so that both sides of the sashes may be cleaned, glazed or otherwise worked upon from the inside of the room. The main object of the invention is to provide simple means whereby this may be accomplished not only on new windows but as readily on windows already installed. A further object is to so construct this means that they will not interfere with the normal operations of the sashes nor materially alter any of the parts of the window. Another object is to so construct this means that they may be employed on windows of all sizes. A still further object is to provide means which may be manufactured and installed at a comparatively low cost.

These and various other objects and advantages will be readily understood from the following description and from the accompanying drawings of a preferred embodiment of the invention in which, however, certain modifications may be made without departing from the scope of the appended claims. In the drawings

Fig. 1 is a sectional elevation of a window to which my invention has been applied;

Fig. 2 a similar view, but with certain parts removed;

Fig. 3 a similar view showing the lower sash swung into the room;

Fig. 4 a similar view showing the upper sash swung into the room;

Fig. 5 is a fragmental front view of a window shown with both sashes swung into the room,

Figs. 6 to 11 show various parts and details of the construction.

Referring now to the drawings, Figs. 1 and 2 show a window in which the casing is shown at 10, the upper sash at 11, the lower sash at 12 and the stop bead at 13. The lower part of the stop bead is removable and is secured to the casing by a bolt 14 and two plates 15 and 16 attached, respectively, to the stop bead and the casing by screws 17 and 18. These parts are plainly shown in Figs. 7 and 8. The plate 16 is provided with a key hole slot 19 in which the bolt 14 slides. The bolt is of a square cross-section below the head to prevent it from turning in the slot. The plate 15 is provided with a straight slot 20 in which the other end of the bolt slides, and the bolt is provided with a nut 21 for clamping the plates together.

When it is desired to swing the lower sash 12 into the room, the stop beads 13 on both sides of the casing are removed by unloosening the nut

21 and lifting the bolt 14 until its head will pass through the upper part of the key hole slot 19. After the stop beads are removed the sash is lifted slightly above the apron 22 and pulled inward. A pivot 23 is driven up in the lower frame 60 of the lower sash close to the left hand side of the sash. The operating end 24 of this pivot fits in a socket 25 inserted in the apron. A similar socket is inserted in the frame as shown at 26 to accommodate the operating end of the pivot when the 65 lower sash is in its closed position.

A plate 27, having a rearwardly extending housing 28, is secured to the window frame. Normally this plate is almost hidden by the stop bead and is not exposed until the stop bead is removed as 70 in Fig. 2. A swinging pawl 30 is mounted in the housing 28 on a pin 31, and is provided with a pivot point 32. This point fits in a hole 33 drilled in a plate 34 which is secured to the upper frame of the lower sash.

After the lower pivot has been located in the socket in the apron, the pawl 30 is swung out from its housing, as shown in Fig. 5, and the pivot 32 inserted in the hole 33. The pawl is maintained in any position by a spring 36 which is secured to the housing by a rivet 37. While the sash has been manipulated in the manner just described, it has been supported by the weighted chains 38 which pass over the pulleys 39. If the chain, opposite to the end on which the frame is pivoted, is removed the sash may be swung around to any angle. To restore the sash to its normal position, the just described action is reversed.

The upper sash 11 is manipulated in practically the same manner. Reference is now had to Figs. 90 3 and 4, in which opposite sides of the window casing is shown, and to Fig. 10, which show the construction of the parting strips 40. A section 41 of the parting strip is loosely mounted by means of tongues 42 and 43 which fits behind the rigidly 95 mounted part 40 of the parting strip. When it is desired to swivel the upper sash, the sections 41 are removed from both sides of the casing by lifting the sections and swinging the lower tongues 43 out of engagement with the lower parts of the 100 parting strips. The upper sash may now be lowered and passed between the spaces formerly occupied by the sections 41, after which it is pivoted exactly as in the case of the lower sash, except that it is pivoted on the opposite side of the 105 apron, so as to swing oppositely to the lower sash. The chain 44, which passes over the pulley 45 remains attached to the sash while the opposite chain is removed.

Reference is now had to Figs. 9 and 11, which 110

show a fragmental side view of either window sash and certain details used in connection with the sash chain. The chain 44 is accommodated in the customary groove 46, milled in the side 5 of the sash, and is secured to the sash by means of an eye 47, which hooks on a hook 48 secured in the sash. A socket 49 is counterboarded across the groove 46 to house the spiral spring 50. The chain is inserted between the windings of the 10 spring, so that it is firmly secured to the chain. The whole length is within the socket 49, so that it does not interfere with the raising and lowering of the sash, furthermore, a screw eye 51, for guiding the chain, is secured directly below the socket. 15 When the chain is removed from the sash the spring 50 prevents the free end of the chain from being drawn through the pulley, as plainly shown in Fig. 4.

While I have described and illustrated the pivots 20 and sockets as mounted on opposite sides of the apron, it is evident that the pivots may be secured on the same side of each sash, so that one socket in the apron and one pawl on the window frame will suffice. Likewise, the invention may 25 be used with windows constructed of metal as well as of wood.

Having described my invention and its objects, what I claim as new and wish to protect by Letters Patent is:

30 1. In combination with a window comprising a window frame, an upper and a lower sash, stop beads, parting strips and an apron; removable sections provided in the inner stop beads and in the parting strips, a pivot secured near one end of 35 the lower frame of one sash, another pivot se-

cured near the opposite end of the lower frame of the other sash, pockets provided at opposite ends of the apron, hinged pawls secured on opposite sides of the window frames under the removable stop beads and concealed thereby, a pivot associated with each of said pawls, and socket secured in the upper frames of the sashes axially aligned with the sockets in the lower frames so that the sashes may be hinged on opposite sides of the window frame and swung inwardly from this frame. 80 85

2. In combination with a window comprising a window frame, and upper and a lower sash slidably mounted by means of counterweighted cords or chains, stop beads, parting strips and an apron; removable sections provided in the inner stop beads and in the parting strips, a pivot secured near one end of the lower frame of one sash, another pivot secured near the opposite end of the lower frame of the other sash, pockets provided at opposite ends of the apron, hinged pawls secured on opposite sides of the window frames under the removable stop beads and concealed thereby, a pivot associated with each of said pawls, socket secured in the upper frames of the sashes 90 95 axially aligned with the sockets in the lower frames so that the sashes may be hinged on opposite sides of the window frame and swung inwardly from this frame, and means attached to said cords or chains and concealed in sockets 100 105 formed in the sides of the sashes for supporting the counterweights when the cords or chains are detached from the sashes.
